UNITED STATES PATENT OFFICE.

ROBERT F. CUTHBERT, OF NEW YORK, N. Y., ASSIGNOR TO THEO. TIEDEMANN & SONS, INC., OF NEW YORK, N. Y., A CORPORATION OF NEW YORK.

BOX FOR GARMENTS.

Application filed September 23, 1924. Serial No. 739,253.

To all whom it may concern:

Be it known that I, ROBERT F. CUTHBERT, a citizen of the United States, and a resident of the city, county, and State of New York, 5 have invented a new and useful Improvement in Boxes for Garments, of which the following is a specification.

This invention relates to an improvement in a box or container intended for use in 10 holding garments in such condition that the same may be readily shipped or displayed without the same becoming unduly wrinkled or in any way damaged.

My improved box is particularly useful 15 in connection with ladies' dresses or other garments of considerable length which have to be contained in a folded condition in the box and I provide said box with means for holding the garment in such a position that 20 it cannot be shaken about loosely in the box, wrinkled or otherwise damaged.

Reference is to be had to the accompanying drawing, forming a part hereof, in which—

25 Figure 1 is a perspective view of my improved box with its cover removed to show its interior;

Figure 2 is a plan view of the same;

30 Figure 3 is a perspective view of a portion of one end of the box showing a hook for receiving the garment hanger;

Figure 4 is a sectional view on the line 4—4 of Figure 2 looking in the direction of the arrows;

35 Figure 5 is a sectional view of one of the side edges of the box showing one of the spring clips; and

Figure 6 is a perspective view of the portion of the box shown in Figure 5.

40 Throughout the various views of the drawings, similar reference characters designate similar parts.

In the preferred embodiment of my invention shown in the accompanying drawing, 1 indicates the bottom of the box, 2 indicates one of the ends, 3 the opposite end and 4 and 5 the longitudinal sides. The box is preferably made in an elongated form, and the bottom, sides and ends are 45 preferably made of cardboard, thin wood or the like. To add rigidity and strength to the box, the upper edges of the ends 2 and 3 and sides 4 and 5 are provided with a strengthening frame of wood as at 6. This 50 is preferably of considerable thickness and

affords a support for several of the garment-holding means which lie within the box.

The end 2 of the box is provided with a wire hook 7 which is firmly secured into the frame 6 as disclosed in Figure 3. This hook depends downwardly into the box and engages with a hook 8 on a garment hanger 9 on which the garment 10 is held. The upper fold of the garment 10 extends for the full length of the box and at the end of the box 3, said garment is folded over a rod or bar 11 which connects two side pieces 12, the inner ends of said side pieces 12 being pivoted at 13 to the frame 6 of the box at its opposite side edges 4 and 5.

A pivoted frame is thus provided, the same consisting of the side edges 12 and cross-bar 11. Said frame is capable of being pivoted about the pivots 13 so that its free end where the bar 11 is located, can 71 be lifted up and out of the box when it is required to remove the garment.

In Figure 4, the beginning of this pivotal movement of the frame is disclosed in dotted lines. The underfold of the garment, shown 80 at 14 extends back towards the end of the box 2 and at a position intermediate of the hook 7 and movable frame is a cross-strip 15 which is secured to the bottom of the box in any suitable way such as by tacks or pins 16. At 17 are shown spring clips which are preferably held in position by the cross-strip 15 which lies over the downwardly and inwardly bent portions 18 and 19 of these clips. These clips engage with the 90 side edges of the underfold 14 of the garment near its lower end and hold the same from shifting within the box.

It will be seen that the clips are so formed that they in no manner can injure the garment, yet they hold the lower end of the same taut enabling the garment to be drawn snugly over the cross-bar 11 and thence up towards the end 2 of the box where the hook 8 on the hanger 9 is caused to engage 100 with the hook 6 on the box.

The garment when in its proper position in the box is held under considerable tension and it cannot shift above the box in any way, although it may be readily removed for display by disconnecting the hook 8 from the hook 6, disengaging the end of the garment from under the clips 17 and then lifting the frame and drawing a garment from under it.

From the foregoing, it is obvious that my invention is not to be restricted to the exact embodiment shown but is broad enough to cover all structures coming within the scope 5 of the annexed claims.

What I claim is:—

1. A box for holding a garment, said box being provided with fixed spring clips near its side edges for engaging the side edges 10 of the garment near the lower end of the same, a frame pivoted at a distance from one end of the box, said frame being provided with a cross-member located at one end of the box over which the garment is 15 folded, and means at the opposite end of the box for detachably holding the upper end of the garment.

2. A box for holding a garment, said box having means at one end for detachably 20 engaging the upper end of a garment, a pivoted frame near the other end of the box, said frame having a cross member located at one end of the box over which a garment is adapted to be folded, and permanently located spring clips at the bottom of the box and at the longitudinal side edges of the same for engaging the lower 25 end of the garment.

3. A box for holding a folded garment, 30 said box having a member extending trans-

versely, clips at the ends of said member extending on top of the same and adapted to engage a garment at its lower end, a frame having its side pivoted to the sides of the box, said frame having a cross member located at one end of the box when said frame lies within the box, a hook at the end of the box opposite to the end where the frame is located, adapted to receive a garment hanger for supporting the upper end 40 of a garment and adapted to detachably engage said hook.

4. A box for holding a garment, said box having its upper edge surrounded by a thickened frame, a hook in said frame at 45 one end of the box, a movable frame having its side members pivoted in the box frame at the longitudinal sides of the box and at a distance from the ends of said box, a cross bar connecting the free ends of said 50 movable frame at one of the ends of the box, and spaced fixed means on the bottom of the box for detachably engaging and holding the lower end of a garment when the same extends in a folded position over the cross bar on the movable frame.

Signed at the city, county and State of New York, this 18 day of September, 1924.

R. F. CUTHBERT.
